UNITED STATES PATENT OFFICE

LINN BOYD BENTON, OF PLAINFIELD, NEW JERSEY, ASSIGNOR TO AMERICAN TYPE FOUNDERS COMPANY, OF JERSEY CITY, NEW JERSEY, A CORPORATION OF NEW JERSEY

ANGLE-BODY TYPE

Application filed December 19, 1928. Serial No. 327,128.

This invention relates to printer's type, and particularly to the form of type used in printing italics.

An object of the invention is to minimize or eliminate the kerns which have heretofore been necessary with italic type.

Another object is to provide a type for printing in italics which will lock up in the type form securely.

A further object is to provide an italic type which will be easy to handle in composition and in correction and distribution.

Further objects and advantages of this invention will become apparent as the description proceeds.

Referring to the accompanying drawings, which are made a part hereof, and on which similar reference characters indicate similar parts,

Figure 1 is a plan view of several letters set up showing my invention,

Figure 2, a perspective of a single type, showing the configuration of the type form,

Figures 3 and 4 show spaces,

Figure 5, a space called an "end space" which is used for the purpose of squaring up the ends of letters and also for the purpose of using ordinary spacing material between the flat surfaces of the end spaces when one of them has been reversed, and

Figure 6 a view of two adjacent type showing the clearance between the side portions.

As stated, the object of this invention is to provide italic type in which the letters may lie practically on the body of the type and not have excessive overhanging kerns as has been found necessary in making italic type heretofore.

In order to provide for the slant of the letters I have made the body of the type with a slant or angle. The type therefore might be called "angle-body" type.

In the drawings, numeral 10 indicates the body of the letters upon which the letter 11 itself may be formed. In order to provide for the slope of the letters I provide the type 10 with sloping sides 12 and 13 and parallel surfaces 14, 15, 16, 17 at right angles to the body. The sloping sides having a clearance

at 30 so that it will not interfere with the perfect lining of one type against another.

The body of the type is cast with the usual printer's nick 18. In order to space the type I provide spaces 19 and 20, the space 20 being a double spacer. These spaces have parallel portions 21 and 22, which correspond to the parallel portions 16 and 17 on the body of the type. The opposite side of the spaces have parallel portions 23 and 24 which correspond to the parallel portions 14 and 15, respectively, of the type body.

Figure 5 shows another form of space for squaring up the end of a line of type. This space has parallel portions 25 and 26 which correspond to the similar portions 21 and 22 of the space 20. The opposite side 27 of this space is a plane face at right angles to the back 28 of the space. The end space 29 shown in Fig. 1 is similar to that shown in Fig. 5 in detail, but in inverted position, having a wide front and narrow back.

It will be obvious to those skilled in the art that various changes may be made in my device without departing from the spirit of the invention, and I therefore do not limit myself to what is shown in the drawings and described in the specification, but only as set forth in the appended claims.

Having thus fully described my said invention, what I claim as new and desire to secure by Letters Patent, is:

1. An end space for printing type for slanting letters having a relatively wide back or belly, parallel to the line of print, and one side at right angles to the line of print and the other side formed by a sloping surface and two parallel sides of different lengths at right angles to the line of print, substantially as set forth.

2. A printing type for slanting letters having front and back portions parallel to the line of print, and slanting side portions, the sides each having parallel surfaces at right angles to the body, the upper and lower parallel surfaces on one side of the type being of unequal width and those on the other side being of unequal width in the reverse order whereby a clearance is provided between ad-

jacent type when the type are set up, substantially as set forth.

3. A printing type for slanting letters having front and back portions parallel to the line of print, and side portions composed of three faces two of which are unequal in width and lie in parallel planes, the third of which lies in a plan oblique with respect to the other two planes, substantially as set forth.

4. A printing type for slanting letters having front and back portions parallel to the line of print, and slanting side portions, the sides each having parallel surfaces substantially at right angles to the front and back portions, the upper and lower parallel surfaces on one side of the type being of unequal width and those on the other side being unequal in width in the reverse order whereby a clearance is provided between adjacent slanting side portions of the type when the type is set up, the side portions lying in two opposite parallel planes connected by a third surface which lies in a plane oblique with respect to the parallel portions, substantially as set forth.

5. A spacer for printing type for slanting letters comprising a relatively thin plate having the central portion of its opposite sides lying in parallel planes oblique to the line of print, each of these planes terminating in upper and lower surfaces which lie in planes at right angles to the line of print, the surface of one side at the front of the type being unequal in width with that forming the opposite side and the surface forming the plane at one side at the back of the type being also of unequal width from the plane of the opposite side but in the reverse order, substantially as set forth.

In witness whereof, I have hereunto set my hand at Jersey City, New Jersey, this eighteenth day of December, A. D. nineteen hundred and twenty-eight.

LINN BOYD BENTON.
